UNITED STATES PATENT OFFICE.

FREDERICK T. MANLEY, OF HOUSTON, TEXAS, ASSIGNOR TO THE TEXAS COMPANY, OF NEW YORK, N. Y., A CORPORATION OF TEXAS.

APPARATUS FOR CRACKING HYDROCARBON OILS.

Application filed October 10, 1917. Serial No. 195,774.

To all whom it may concern:

Be it known that I, FREDERICK T. MANLEY, a citizen of the United States, residing in Houston, Harris County, and State of Texas, have invented certain new and useful Improvements in Apparatus for Cracking Hydrocarbon Oils, of which the following is a specification.

The apparatus constituting the subject matter of this application was designed by me as an efficient and convenient means for performing certain novel processes of cracking hydrocarbon oils invented by me and made the subject my separate applications for patents Serial numbers 195,775 and 195,776, filed October 10, 1917, but it is to be understood that this apparatus is not limited in its use to the carrying out of those particular processes. The novel features of construction and the novel methods of operation thereby permitted will be apparent from the following description taken in connection with the accompanying drawing in which—

25 Figure 1 shows the apparatus partly in vertical section;

Figure 2 is an enlarged section of a portion of the cracking still showing scraping means therein.

30 Referring to the drawing, a cracking still 4, with suitable supports 9, is heated intermediate its ends in a furnace 1, having a baffle wall 3, burner 2, and stack 13. A vapor line 5, extends from the upper portion of the cracking still above the heating zone to an air condenser 6. A conduit 7, reaches from the air condenser directly to the lower portion of the cracking still below the heating zone in order to return condensed material. 35 8 is a valved draw-off pipe at the bottom of cracking still 4. The still is preferably equipped with a supply pipe 10 entering the horizontal section of the conduit 7, whereby the introduction of the oil charge is caused to produce an injector effect by which the condensate in the pipe 7 is forced into the bottom of the still. The supply pipe has a check valve 11 of any well known form.

40 A vapor pipe line 15 extends from the air condenser 6 to a water condenser 28, the outlet from the water condenser 28 being fitted with a valve 29. 16 denotes a pressure gauge on the air condenser to indicate the vapor pressure therein. 17 and 18 designate recording thermometers in the air condenser

and cracking still, and 19 and 30 furnace pyrometers. A gauge 14 for indicating the liquid level in the still 4 is situated at the upper part thereof. In this form of apparatus the hydrocarbon oil in the cracking still 4 form an extended vertical column and as the oil charge and condensate is forcibly supplied near the bottom it passes upward through the column and is cracked in its passage.

45 In order to keep the inner surface of the cracking still clean and prevent the collection of material on that surface I preferably provide the device with scraping means shown in detail in Figure 2. The scraping means includes a shaft 24 extending centrally down into the cracking still and engaging any suitable bearing at the bottom. This shaft carries steel brushes 25, brushes being secured to the shaft by the rods 27, around which are placed coiled springs 26 to yieldingly press the brushes against the inner surface of the still 4. The shaft 24 may be driven through a worm gear 21 from the shaft 22. In order to support the shaft at its upper end I preferably mount a pipe 20 in the upper end of the still 4 slightly larger in diameter than the shaft 24, and at the upper end of this pipe 20, I place a stuffing box, 23. The purpose of this pipe 20 is to place the stuffing box in a relatively cool position. The brushes in the tube 4 are placed only in the cracking zone which, as illustrated in Figure 1, is between the parts marked 4^a and 4^b.

50 The heating arrangements of the furnace are such that the hot combustion gases pass upward from the burner 2 between the furnace wall 1, and baffle 3, until they are deflected by the top wall of the furnace into the heating chamber formed by the baffle 3 and in which chamber is the cracking still. The hot gases pass downwardly imparting heat to the cracking still, and find exit at 31 to and through the stack 13. The upper and lower ends of the cracking still preferably extend beyond the heating zone.

55 As an illustration of the method of use of my apparatus I may charge the still 4 with the hydrocarbon oil which it is desired to crack through pipe 10, the liquid level of the oil being maintained at a point above the heating zone, in the upper portion of the still. The hydrocarbon may be heated to a temperature of from 650° to 800° F. and a

110

suitable pressure may be maintained by means of valve 29 in the condenser outlet. The temperature and pressure may be varied in accordance with the character of oil treated 5 and of the products desired. I may use a pressure as high as 300 lbs., but ordinarily the pressure used is not below 100 lbs. Vapors generated in still 4 pass directly through vapor line 5 to air condenser 6, 10 where the heavier constituents, ordinarily predominantly of the kerosene type, are condensed, while the lighter constituents, ordinarily predominantly of the gasoline type, pass through vapor line 15 to water condenser 28, and are condensed. The hydrocarbons condensed in air condenser 6 are directly returned for further decomposition 15 through pipe 7 to the bottom of still 4, and are forced into and through the column of hydrocarbon maintained there.

In another method of use of my apparatus I may charge the still with residuum or other heavy hydrocarbon oil through pipe 32 and heat it to produce the desired cracking temperature, which may ordinarily vary 25 from 650° to 800° F. I may then introduce a lighter hydrocarbon oil of lower boiling point, which it is desired to crack, such as kerosene distillate or gas oil, through supply 30 pipe 10, the lighter oil being decomposed in its passage through the heavier oil. The vapors pass from still 4 through vapor line 5 to an air condenser 6, where heavier constituents thereof are condensed, the lighter 35 vapors such as those of the gasoline or naphtha type passing through vapor line 15 to water condenser 28. The hydrocarbons condensed in air condenser 6 flow back through pipe 7 to the bottom of still 4 and are forced 40 through the column of heated hydrocarbon oil maintained therein for further decomposition by an ejector action due to the inward flow of fresh oil through the pipe 10. Any desired pressure may be maintained in 45 the system by manipulation of valve 29 on the condenser.

It is readily apparent that my apparatus is adapted for other methods of operation.

What I claim and desire to secure by Letters Patent is:

1. Apparatus for cracking hydrocarbon oils comprising a relatively tall vertical still, means for introducing a heavy oil and maintaining it at a substantially constant level 55 in said still, means for heating the still intermediate its ends to maintain the heavy oil therein at a cracking temperature, a separator connected to receive vapors from the top of the still, a condenser connected to the separator, a liquid return pipe connected directly from the separator to the bottom of the still, and means for forcing the liquid 60 from the return pipe through the body of the heavy oil in the still.

2. Apparatus for cracking hydrocarbon

oils comprising a relatively full vertical still, means for introducing a high boiling point hydrocarbon oil and maintaining it at a substantially constant level in the still, means for heating the still to maintain the oil at a cracking temperature, a separator connected to receive vapors from the top of the still, a condensate return line connected directly from the separator to the bottom of the still, and means for forcing the condensate from 70 the return line through the body of oil in the still.

3. Apparatus for cracking hydrocarbon oils comprising a relatively tall vertical still, means for introducing a heavy oil and maintaining it at a substantially constant level 80 in said still, means for heating the still intermediate its ends to maintain the heavy oil therein at a cracking temperature, a separator connected to receive vapors from the top of the still, a condenser connected to the separator, a liquid return pipe connected directly from the separator to the bottom of the still, and an inlet connection for forcibly supplying fresh oil into the return 90 pipe near the still to force the liquid from the return pipe with the fresh oil through the body of oil in the still.

4. Apparatus for cracking hydrocarbon oils comprising a still, means for introducing 95 a high boiling point hydrocarbon oil and maintaining it at a substantially constant level in the still, means for heating the still to maintain the oil at a cracking temperature, a separator connected to receive vapors 100 from the top of the still, a liquid return line connected directly from the separator to the bottom of the still, and an inlet connection for forcibly supplying fresh oil into the return pipe near the still to force the liquid 105 from the return pipe with the fresh oil through the body of oil in the still.

5. Apparatus for cracking hydrocarbon oils comprising a still, a charging line at the bottom, a vapor line at the top, a separator to which the vapor line is connected, a liquid return pipe connected directly from the bottom of the separator to the bottom of the still, a second charging line leading into the return line near the still, and discharging thereinto in the direction of flow of oil therethrough, adapted to force the liquid from the return line through the body of oil in the still.

6. Apparatus for cracking hydrocarbon 120 oils comprising an elongated vertical still, means surrounding the still intermediate its ends for subjecting the contents thereof to a cracking temperature, means for introducing oil into the bottom of the still and 125 below the heating zone and maintaining a substantially constant level therein, means connected to the vapor space above the level of the oil in the still for receiving the evolved vapors and separating out the un- 130

converted portions, means for directly returning said unconverted portions from said separating means to the bottom of the still below the heating zone and for forcing them upwardly through the entire body of the heated oil in the still, and means operated during the cracking operation for removing carbon deposited on the walls of the still and permitting it to gravitate out of the 10 heating zone.

7. Apparatus for cracking hydrocarbon oils comprising an elongated vertical still, a furnace surrounding the still intermediate its ends for imparting a cracking heat here- 15 to, means for receiving the evolved vapors and separating out the unconverted portions, and means directly connecting the separating means and the bottom of the still and including a device located adjacent to lower 20 end of the still and traversed by fresh charging oil for forcibly injecting the separated condensate into the still in conjunction with the fresh oil.

8. Apparatus for cracking hydrocarbon 25 oils comprising a vertical still maintained under pressure, a furnace surrounding the still intermediate its ends for heating the oil therein to a cracking temperature, a pipe

for supplying oil under pressure to the bottom of the still, means connected to the 30 vapor space of the still for separating out the heavier constituents of the evolved vapors, and a return pipe directly connected from said separating means to said supply pipe for returning the condensate to the 35 bottom of the still, said return pipe having a U-bend at the point of condenser with said supply pipe.

9. Apparatus for cracking hydrocarbon oils comprising a cracking still maintained 40 under pressure, means for heating the still intermediate its ends to a cracking temperature, a pipe for supplying a stream of charging oil under pressure into the lower end of the still, means for receiving the evolved 45 vapors and separating out the heavier constituents thereof, a return pipe directly connecting the separating means and said supply pipe for returning the condensate to the bottom of the still, and means for positively 50 forcing the condensate into the charging oil traversing said supply pipe.

In testimony whereof I do affix my signature.

FREDERICK T. MANLEY.
